CLAIM

I claim the ornamental design for a blade, as shown and described.

DESCRIPTION

FIG. 1 is a perspective view of a blade; and, FIG. 2 is a top view of the blade of FIG. 1.

The uneven broken lines represent boundaries of the design and form no part of the claimed design. The even broken lines represent portions of the article that form no part of the claimed design.

1 Claim, 2 Drawing Sheets(56)
